UNITED STATES PATENT OFFICE.

CHARLES READ, OF NEW YORK, N. Y.

SPIKE.

1,112,557.

Specification of Letters Patent.

Patented Oct. 6, 1914.

Application filed October 11, 1912. Serial No. 725,290.

To all whom it may concern:

Be it known that I, CHARLES READ, a citizen of the United States, and resident of the borough of Brooklyn, county of Queens, 5 city and State of New York, have invented certain new and useful Improvements in Spikes, of which the following is a specification.

This device is intended for use in railroad 10 construction and may be somewhat correctly called a rail fastener, although because of its outline and a certain portion of the operation connected with its use, I prefer to call it an improved spike.

15 Besides its cheapness this device offers many advantages over the ordinary spike, such as increased efficiency particularly in holding strength, ease with which a more or less permanent locking is secured, and resistance against wear or loosening by vibration. Other advantages will be set forth as the specification progresses.

The following is what I consider the best means of carrying out this invention.

20 25 The accompanying drawings form a part of this specification, in which:

Figure 1 is a central vertical section, through the spike and parts operable therewith. Fig. 2 is a corresponding view 30 though in this figure the spreading tool is shown in position. Fig. 3 shows a plate that may be used in the upper end of the device as a closure.

Similar reference numerals indicate like 35 parts in all the figures where they appear.

At 1, I have shown the body portion of the spike, which is constructed of four angular plates of sheet steel joined together at 2, and forming a pyramid, which when the 40 device is in operation is inverted. The member 1 is formed of sheet steel of a sufficient thickness, and is square in cross section. The edges where the separate sides are joined together may be either a folded 45 edge or, if an open cut, should be welded together. I deem it advisable to reinforce the point 2 by allowing a quantity of metal to gather there, if the device is electrically welded there will be no difficulty in reinforcing the point. A short distance from 50 the top of each of the plates or side members I have produced a rib, or deflected portion 3, for a purpose that shall appear later, and farther down on two of the directly opposite sides I have produced a window 4 by shearing and forcing inward a tongue 5.

This tongue 5 should be somewhat narrower than the whole width of the side from which it is produced so that the side will not be too greatly weakened. The lower end of this 60 tongue 5 is sheared in such a manner as to force it slightly outward as shown at 6. I intend that this spike shall be driven and as I have found it difficult to drive on the upper open end 7, I have provided a drive 65 plate 8, which may be of a good grade of steel, and which is provided with a four sided channel 9 on its under side which is adapted to fit over the upper edges 10 of the member 1. The force of the hammer blow 70 will be received by the upper face 11 of the member 8. Before commencing the operation of driving this spike the point or lower end of the body should be passed through a square hole 12 in the washer or holding 75 down plate 13, and it is my intention that the hole 12 shall be of such a size that it will frictionally engage with the sides of the member 1 even before the projections 3 meet the upper side of the plate 13. 80

In placing my spike in operation it is my intention that it shall first be driven to the depth of the line 14 after which the spreading tool shown in Fig. 2 is inserted and the tongues 5 are forced out into the position of 85 the dotted line A. The tool is then removed and the driving completed and when the spike is in the finished position the tongues 5 which have assumed the position of the dotted lines B reliably hold the spike secure 90 against a possible loosening by vibration or any other means. The spreading tool before referred to consists of a plurality of jaws 20 each provided with a shoulder 21 which also serve as a stop preventing the jaws 95 from entering the member 1 to too great a depth, and a seat 22 intended to engage and bear in the hollow caused by the forming of the projection 3, and a projection 23 intended to operate against and force outward the 100 tongues 5. A screw-threaded and tapered spindle 24 passes between the jaws 20 and terminates in a squared head nut 25 for the reception of a wrench. Rotating the nut 25 causes the lower ends of the jaws 20 to be 105 forced away from each other and causes the projections 23 to force the tongues out into the position shown in Fig. 2. It is not necessary to provide a plate 8 and tool 20 for each of the spikes as one plate and one tool 110 may serve for a great length of time.

A feature of my device not before re-

ferred to, but one to which I attach great importance is made possible by the peculiar construction of my spike. After the spike has been driven to its full extent and the fastening completed, it is my intention to fill the hollow body of each spike with a good preservative such as carbolated creosote which will slowly seep through the windows 4 and impregnate the wood surrounding the spike and even at some distance therefrom. If it is found advisable I can produce a second series of perforations 30 in a longitudinal line and through the wall of any or all of the sides.

15 Modifications may be made within the scope of the appended claims without departing from the principle or sacrificing the advantages of this invention.

I have shown my device as constructed 20 with two tongues 5 but I may use one or more. If it is found desirable a certain portion of each side may be omitted as shown by the dotted line 26 and this may be of a certain advantage because it would allow 25 the fibers of the wood to enter the member 1 thereby assisting in the securing of the member. The projection 3 may be formed independently or may be entirely omitted, if omitted perforations should be provided 30 for the teats 22. It will be found that the use of these spikes as a preservative container is extremely desirable and if I choose I may drive a number of spikes of this or a smaller size into the wood of the tie at different points simply that they may distribute their preservative through the 35 whole of the tie. A small metallic plate or cap may be used to close the upper end of the spike after the preservative has been 40 placed therein.

What I claim and desire to secure by Letters Patent is:—

1. A spike formed of four pyramidal side members each member being provided with an integral projection, and certain of said members provided with tongues for securing the whole as specified. 45
2. A spike formed with four pyramidal sides, tongues formed in certain of said sides normally arranged within the plane 50 of said sides in combination with means operable within the body of said spike for forcibly projecting said tongues beyond the plane of said sides as herein specified and for the purpose set forth. 55
3. A spike having in combination a hollow body composed of four sides and tongues formed in two of said sides, projections formed in all of said sides and a plate in frictional engagement with the 60 body as herein specified.
4. A spike of the character described having a body and means in operable relation to said body and adapted to be forced outward therefrom for securing said body 65 against displacement, a spreader for placing in operative position the first said means, and a driving plate reinforcing the sides of said body and for receiving the pressure applied while the spike is being inserted 70 all combined as herein specified and for the purpose set forth.

Signed at New York city, county of New York, and State of New York this 20 day of September 1912.

CHARLES READ.
